DESIGN FOR A SKI KIT

Florence N. Lewis, New York, N. Y.

Application January 14, 1937, Serial No. 67,045

Term of patent 7 years

To all whom it may concern:

Be it known that I, Florence N. Lewis, a citizen of the United States, residing in New York, county and State of New York, have invented a new, original, and ornamental Design for a Ski Kit, of which the following is a specification, reference being had to the accompanying drawing, forming a part thereof.

In the drawing:—

Fig. 1 is a perspective view of a ski kit showing my new design on a slightly enlarged scale and in open position.

Fig. 2 is a view similar to Fig. 1 showing the mirror in unexposed position on the bottom of the bag.

Fig. 3 is a perspective view of the interior of the bag showing the pocket of the bag in an extended position.

Fig. 4 is a perspective elevation of the bag in closed position.

I claim:

The ornamental design for a ski kit as shown and described.

FLORENCE N. LEWIS.
